HERBERT L. MOSES, OF BALTIMORE, MARYLAND, ASSIGNOR, BY MESNE ASSIGNMENTS, TO M. S. LEVY AND SONS, INC., OF BALTIMORE, MARYLAND, A CORPORATION OF DELAWARE.

CONFORMATOR ATTACHMENT FOR HATS.

1,362,343.

Specification of Letters Patent. Patented Dec. 14, 1920.

Application filed June 3, 1919. Serial No. 301,479.

To all whom it may concern:

Be it known that I, HERBERT L. MOSES, a citizen of the United States, residing at Baltimore, in the State of Maryland, have 5 invented certain new and useful Improvements in Conformator Attachments for Hats, of which the following is a specification.

This invention relates to a conformator 10 attachment for hats and has for its object to provide a hat with a permanent conformator of improved construction whereby the hat may be made more comfortable for the wearer.

15 Another object of the invention is to provide an improved construction and arrangement of conformator attachment for hats whereby the hat may be made to accurately fit the head and which will avoid undue pressure around the head and leaving there-around marks when the hat is removed.

The invention is illustrated in the accompanying drawing wherein,—

Figure 1 shows a cross-sectional detail 25 through a hat the crown of which sustains my improved conformator attachment, and

Fig. 2 illustrates on an enlarged scale a portion of a crown and brim with the improved device supported from the wall of 30 the crown and the relation of sweat-band with respect to the improved device.

Referring to the drawing the numeral 5, designates the brim of a hat and 6, the crown thereof. It is not essential to the invention 35 whether the hat be of straw or felt as the invention is readily applicable to either.

My invention resides in the provision of an improved construction and arrangement of flexible band to extend around the interior of the crown between the wall of the latter and the annular sweat-band, and in the novel manner in which that flexible band is sustained.

The flexible band 7, is preferably, al- 45 though not necessarily, formed of elastic material, such as an elastic ribbon or webbing, whereby to enable the same to expand or contract circumferentially and thus enable it to more readily conform to any irregularities in the head and at the same time vary somewhat in circumference to fit heads properly and snugly.

As illustrated in the drawing, I prefer to sustain the band 7, from the wall 8, of 55 the crown by means of stitches or threads

9, which pass through the band at a point removed from both the upper and lower edges 10 and 11 of said band. In the form shown, the stitches 9, extend radially between the crown and band and pass through the band at a point about midway between the upper and lower edges 10 and 11, so that neither of said band-edges is drawn toward the encircling crown wall but both edges are held in a spaced relation from the 60 crown and in substantially the same vertical plane.

The stitches 9, may therefore be said to be radial flexible suspension means by which the band is suspended from the crown wall 70 in a way that both the upper and lower edges of the band are free to conform to the head and to thereby provide a "floating band."

By reference to Figs. 1 and 2, it will be 75 seen that the stitches 9, pass through the band in a horizontal plane and that those same stitches pass through the crown wall 8, at a point elevated with respect to the brim 5, of the hat. It will also be noted that the lower edge 11, of the floating flexible band is slightly elevated with respect to the bottom 12 of the brim.

The construction of the sweat-band 13, is immaterial to the invention, and may be 80 any of the well-known kinds, with or without ventilation features.

In the present instance the sweat-band has a flap 14, at one edge by which it is attached to the base of the crown by means 90 of stitches 15, and from said attached point the sweat-band extends inwardly at 16, and then upwardly at 17, so that the upwardly extending portion 17, will extend around the inner or smaller circumference of the floating band 7. By this means the floating band keeps the sweat-band spaced from the crown wall 8, and the sweat-band 13 conceals the suspension stitches 9, by which the floating band 7 is sustained.

In practice it is found that not only does the floating band enable the hat to conform to the head but that it more securely holds the hat on the head with ease and comfort to the wearer.

Having described my invention, what I claim is,—

1. A hat having a crown and a brim with a sweat-band on the interior of the crown, and a flexible band extending around the 110

2
interior of the crown between the crown-wall and sweat-band but spaced from the crown-wall and securing devices extending from the crown-wall across the space and 5 engaging the flexible band at a point that is spaced from both the upper and lower edges of the flexible band whereby to leave both of said band-edges free but hold the band in a floating position between the 10 crown-wall and the sweat-band.

2. A hat having a crown and a brim with a sweat-band on the interior of the crown, a flexible band interposed between the sweat-

band and the crown-wall but spaced from the latter wall and a series of sustaining 15 threads passing through the crown-wall and extending across the said space to and engaging the flexible band said threads being attached to the flexible band at a point that is spaced from both the upper and lower 20 edges of the flexible band whereby to hold the band in a floating position and leave said upper and lower edges thereof free and flexible.

In testimony whereof I affix my signature. 25
HERBERT L. MOSES.
